(57) **CLAIM**

The ornamental design for a climbing stick as shown and described.

DESCRIPTION

FIG. 1 is a perspective view of a climbing stick showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is an enlarged view of portion of FIG. 1;

FIG. 10 is an enlarged view of portion of FIG. 1;

FIG. 11 is a cross sectional view taken along the line 11-11 in FIG. 3; and,

FIG. 12 is an enlarged view of portion of FIG. 11.

The broken lines illustrate portions of the climbing stick that form no part of the claimed design. The dot-dash broken lines in the drawings indicates cutoff boundaries for the enlarged detailed portion views and form no part of the claimed design.
